UNITED STATES PATENT OFFICE.

CHARLES F. PERHAM, OF LOWELL, MASSACHUSETTS.

LOOM.

No. 841,432.

Specification of Letters Patent.

Patented Jan. 15, 1907.

Application filed May 1, 1905. Serial No. 258,167.

To all whom it may concern:

Be it known that I, CHARLES F. PERHAM, of Lowell, in the county of Middlesex and State of Massachusetts, have invented certain new and useful Improvements in Looms, of which the following is a specification.

This invention relates to looms, and has for its object to provide improved means for effecting a disconnection of the driving power when one or more warp-threads become broken or so entangled as to form a "float."

To this end the invention consists of a device comprising detectors which are adapted to rest upon the warp-thread and to drop by gravity in the absence of warp-threads and so to cause the lay-beam to actuate suitable mechanism adapted to release the shipping-lever by means of which the driving power is connected to the driving-shaft.

On the accompanying drawings, forming a part of this specification, Figure 1 shows in vertical section a portion of a loom equipped with a device of which the invention consists. Fig. 2 is a front elevation of a portion 25 of the warp-detectors. Fig. 3 is a plan of the power-releasing mechanism. Fig. 4 is a perspective view of a fragment of the reciprocating feeler. Figs. 5 and 6 illustrate the mechanism whereby the lay effects the release of the power.

The same reference characters indicate the same parts in all the figures.

The invention herein illustrated is applicable to any loom of standard pattern having the principal parts arranged as shown by Fig. 1.

10 indicates the right-side frame; 11, the breast-beam; 12, a shaft; 13, the lay carrying the reed 14; 15, the heddles; 16, the arch; 17, the lease-rods, and 18, the warp.

19 is the shipper-rod, mounted on the frame 10 and adapted to move a suitable clutch (not shown) into and out of engagement with a source of power.

20 is a shipper affixed to the rod 19 and extending through a slot 21 in a bracket 22, secured to the frame 10.

A spring 23 on the rod 19 normally holds the clutch out of engagement, forcing the shipper 20 in the direction indicated by the arrow in Fig. 3.

When the shipper is moved against the tension of the spring 23 to the position shown by Fig. 3, it catches upon a shoulder 24 in the slot 21 and remains there until disengaged. Meanwhile the power is applied,

causing the shaft 12 to rotate, the lay to oscillate between the breast-beam 11 and the heddles 15, and the heddles to reciprocate vertically to shift the warp-threads 18.

6c

25 is a lever pivoted at 26 to the bracket 22. One end of said lever extends between the shipper 20 and a stop-pin 27, and the other end is pivotally connected to the forward end of a rod 28. The rear end of the rod is 65 mounted and adapted to slide in a bracket 29, fastened to the frame 10. A spring 30 normally holds said rod forward and the outer end of the lever 25 against the stop-pin 27.

31 is a latch pivoted to the rod 28 and 70 adapted to be engaged by a bunter 32, affixed to the lay 13 when held in the path of movement thereof. The latch 31 is adapted to be lifted by means hereinafter described and held in the path of movement of the 75 bunter 32 (see Fig. 6) when the warp-threads break or form a float. When in this position, the bunter forces the latch and the rod 28 toward the rear, against the tension of the spring 30, and causes the lever 25 to force the 80 shipper over the shoulder 24. When the shipper is thus released, the spring 23 acts, as already described, to disengage the driving-clutch from the source of power. This mechanism for disengaging the driving-clutch is 85 similar to that shown in Letters Patent No. 654,915, granted July 31, 1900, and is merely supplementary to the present invention, which is the means hereinafter described for controlling said mechanism.

90

33 is a girth which extends laterally across and above the warps 18 between the heddles and the lease-rods and which is suitably secured to the upright portions of the arch 16. Said girth constitutes a guide for a reciprocating feeler 34, of which the upper surface is serrated to form abutments 35 and notches 36.

95

37 is a pin projecting from the feeler 34 and connected to one end of a strap 38. Said strap extends over an idle pulley sector or 100 segment 39, pivoted upon a stud 40, and has at its other end a yoke 41, through which the free end of the latch 31 extends.

The yoke 41 is connected by a helical spring 42 to the free end of a lever 43, pivoted on a stud 44 in the frame 10. Said lever has a trundle-roll 45, which co-operates with a cam 46, affixed to the shaft 12, so that each time the cam revolves it causes the strap 38 to draw the feeler 34 toward one 105 side of the frame, a spring 47, connected to the pin 37, serving to return the feeler to its

110

normal position. By reason of this construction the feeler 34 is reciprocated laterally and the yoke 41 raised and lowered constantly during the operation of the loom.

5 The latch 31 is normally held up in the path of the bunter 32 by the yoke 31 and the spring 37, as in Fig. 6, and it drops by gravity when the yoke 41 is drawn down by the lever 43 and the spring 42, which is stronger than 10 the spring 47 at the upper end of the strap 38. The cam 46 is so timed as to depress the lever 43 during the rearward movement of the lay and the bunter 32.

15 50 are a plurality of warp-detectors, which are adapted to coöperate with the abutments 35 of the feeler 34. They straddle the feeler 34 and hang loosely in vertical guides in the girth 33. Each detector has one leg which extends below the girth 33 and a 20 lateral extension 51 at the end thereof. The extensions 51 are adapted to rest upon the warps and to be supported thereby so that the spanning portions 52 may be above the tops of the abutments 35. The spacing of 25 the detectors and the length of the extensions 51 is optional; but in the present instance they are so arranged and constructed that each engages several warp-threads.

30 It will be observed by inspection of Fig. 2 that the extensions 51 overlap slightly, thereby forming a practically continuous extension, so that the warp-threads cannot become lodged between them.

35 As the heddles shift the two sets of warp-threads, first one set and then the other engages and supports the detectors, the feeler 34 reciprocating meanwhile during the periods when the detectors are raised.

40 If it happens that two or more adjacent warp-threads become broken or so entangled as to cause an open space through which one of the detectors might drop, the portion 52 of the detector drops upon the feeler 34 and into one of the notches 36 and upon subsequent action of the cam 46 locks the feeler and the strap 38 and yoke 41 by engagement with one of the abutments 35 of the feeler. 45 The action of the cam 46 and arm 43 is therefore spent in distending the spring 42, connected to the yoke, and the latch 31 remains

in the path of the bunter 32, as in Fig. 6, effecting the disconnection of the driving power, as already described.

It will be observed that the abutments 35 of the feeler are shaped like ratchet-teeth, so 55 that if a detector should drop while the yoke and latch are depressed it would permit the feeler to be returned by the spring 37 to its normal position, thus elevating the latch before locking the feeler. 60

Having thus explained the nature of the invention and described a way of constructing and using the same, although without attempting to set forth all of the forms in which it may be made or all of the modes of 65 its use, I declare that what I claim is—

In a loom, the combination with means for disconnecting the power, of a reciprocatory member extending across and above the warp in a fixed guide, a plurality of detectors 70 mounted in said guide and independently movable transversely with relation to said reciprocatory member, said detectors being adapted to engage either said member or the warp-threads and to be held out of engagement with said member by the warp-threads, power-actuated yielding means for moving said member in one direction, yielding means of relatively less strength for moving said member to normal position, a plurality of 80 abutments on said member adapted to be engaged by said detectors and to be locked thereby against movement with said power-actuated yielding means, a bunter on the lay, a movable latch adapted to be engaged and 85 moved by said bunter and to be moved out of the path of movement of said bunter by said power-actuated yielding means when said reciprocatory member is free to reciprocate, and means connected to said latch and 90 movable therewith when moved by said bunter for effecting the actuation of said means for disconnecting the power.

In testimony whereof I have affixed my signature in presence of two witnesses.

CHARLES F. PERHAM.
